UNITED STATES PATENT OFFICE.

OCTAIVE S. PAYZANT, OF NEW YORK, N. Y.

INTERLINE-TICKET GUIDE.

1,366,275.

Specification of Letters Patent. Patented Jan. 18, 1921.

Application filed November 4, 1919. Serial No. 335,705.

To all whom it may concern:

Be it known that I, OCTAIVE S. PAYZANT, a citizen of the United States, and a resident of the city of New York, borough of 5 Manhattan, in the county and State of New York, have invented a new and useful Interline-Ticket Guide, of which the following is a full, clear, and exact description.

10 This invention relates to holding members or guides for interline tickets of railways and the like, and has for an object to provide an improved construction which can be used with any size ticket and hold same 15 in proper position so that only one ticket can be removed at a time.

Another object in view is to provide a cabinet and holder or guide for either cardboard tickets or folded tickets wherein 20 the tickets are held in proper place, but are capable of vending regardless of their thickness or number of folds.

A still further object in view is to provide a holder or guide for a ticket cabinet 25 which will hold a stack of tickets of any height in proper shape and allow the tickets to be fed from the top thereof one at a time.

In the accompanying drawing:

30 Figure 1 is a front view of the upper part of a cabinet with a holder or guide shown in connection therewith the same embodying the invention.

Fig. 2 is a perspective view of a holder 35 or guide disclosing an embodiment of the invention.

Fig. 3 is a fragmentary sectional view, on an enlarged scale, through Fig. 1 on line 3-3.

40 Fig. 4 is a horizontal sectional view through Fig. 3 approximately on line 4-4.

Referring to the accompanying drawing by numerals, 1 indicates a cabinet provided with various compartments 2, provided by 45 the walls of the cabinet 1 and the various partitions 3, each partition being provided with a series of slots 4 arranged preferably at an angle as indicated in Fig. 3. The various compartments 2 may extend for the 50 full height of the cabinet or for part of said height as desired, and may receive a series

of shelves 5 in any of the grooves 4. As shown at the left in Fig. 1 a number of the shelves 5 have been provided and different quantities of tickets 6 arranged thereon, each set of tickets being supplied with a holder or guide 7. It will be noted that any desired number of tickets may be arranged on any shelf 5 and then a guide 7 provided on top of the stack of tickets for holding the tickets in proper place and allowing one ticket to be moved at a time.

The cabinet 1 and the partitions 3 in addition to being provided with the slots 4 are provided with vertical grooves 8 for accommodating the guiding ears 9 on the guides 7 and also provided with cut out portions 10 and 11 for accommodating certain parts of the guides 7 as shown in Fig. 4. This guide is preferably stamped from one piece of 70 metal, but if desired could be made from several parts and built up to the shape illustrated.

As shown in Fig. 2 the guide is made from one piece of metal and is bent for producing a bottom 12 from which upstanding sides 13 and 14 extend, said sides slightly flaring so as to pinch against the partitions 3. The material of which the guide is made is preferably metal, as for instance brass, 80 and is consequently resilient so that the sides 13 and 14 will properly grip the sides of the various partitions 3, or one of the partitions and the cabinet 1. The bottom 12 is provided with a comparatively deep 85 cut out portion or notch 15 through which the fingers of the operator extend when it is desired to remove a ticket. The sides 13 and 14 extend forwardly and are bent over at 16 and 17 and are formed at the front 90 with a card receiving section 18 and a gripping tongue 19 which may be bent back or forth as desired for producing an adjustment to prevent more than one ticket from being vended at a time. The section 18 is 95 provided with a turned up flange 20 and with spurs 21 for holding a suitable card 22 in place, said card having the name of a town placed thereon and the price of the ticket to said place. In bending the ends 100 16 and 17 offsets 23 and 24 are provided whereby the lower part of the bent ends 16

and 17 may fit into the notches 10 and 11 as shown in Fig. 4, whereby the rear edges 25 and 26 are offset from the inner faces of the respective partitions 3, so that a ticket passing outwardly cannot strike these edges. As shown in Fig. 4 the tongue 19 usually extends a short distance beyond the edge of the cabinet 1 and acts as a stop against which the hand may rest while the 10 finger or thumb extends into the notch 15 and presses against the ticket preparatory to removing the same. It will be understood that in removing the ticket the same is merely pressed downwardly and then the 15 finger is moved outwardly, the friction between the finger and the ticket being sufficient to cause the ticket to slide out over the tongue 19. The tongue 19 is originally set at proper position, or is bent to be in the 20 way of a second ticket and thereby allow only one ticket to be vended at each vending operation. The rear ends of the walls 13 and 14 are bent at 13' and 14' so that the 25 guide may be easily inserted at any time. It will be noted that the side walls 13 and 14 are of some appreciable height. This 30 is to allow space for the fingers when removing tickets. By this arrangement an upper shelf 5 cannot be placed any closer to a lower bunch of tickets than the top edge of the sides 13 and 14, thus leaving ample space for the fingers. As the tickets 35 are vended the guide 7 is gradually moved downwardly following the tickets so that the guide is always resting on or pressing against the tickets so as to hold the same in proper place and at the same time permitting the vending of one ticket at a time.

The guide 7 may be used when vending 40 stiff card board tickets if desired, but is preferably used in connection with what is known as interline tickets in the railroad ticket selling agencies. The interline tickets are usually printed on comparatively thin 45 paper and are comparatively long, for instance ranging from a few inches to six or eight feet. Heretofore large cabinets or racks were provided in which the tickets might be suspended vertically. This way of 50 holding the tickets necessitated a large space and also caused the railroad companies to vend these long or interline tickets at specified windows. The present invention is intended to permit the vending of these long 55 tickets at any window and in a similar manner as though they were card board tickets. The tickets are folded until they properly fit in the various compartments 2 and are stacked in a folded condition on the respective shelves 5 after which the guides 7 are 60 placed in position and pressed down on the stack of folded tickets. When any ticket is desired the ticket seller will place his finger on the top ticket through the notch 15 and 65 press down and pull outwardly whereupon

the top ticket will slide out and the remaining tickets will remain in place or be held in place by the tongue 19 or section 18.

What I claim is:

1. A ticket guide of the character described comprising a bottom, a pair of side members, said side members being formed with projecting downwardly extending ends, said ends merging together for presenting a card receiving section, said bottom being cut away from the card receiving section an appreciable distance toward the rear end of the bottom, and a tongue extending from the card receiving section, said tongue being positioned to prevent the removal of more than one ticket at a time. 70

75 2. A ticket guide of the character described comprising a bottom member, a pair of upstanding side members formed with forwardly and downwardly extending projections, said projections being offset laterally, and means connecting the forward end of said projections acting to prevent the removal of more than one ticket at a time from beneath the guide. 85

90 3. In a device of the character described the combination with a cabinet having chambers, each chamber having the side walls formed with facing grooves and facing notches at the open side thereof, of a 95 ticket guide formed with sides having projecting ears projecting into said facing grooves and offset end members fitting into said notches, and means connecting said end members presenting a tongue for preventing the removal of more than one ticket 100 from said compartments at a time. 100

105 4. A ticket guide of the character described formed from a single piece of sheet metal cut and bent into shape so as to produce an integral construction having a bottom member for engaging tickets, resilient side members presenting a finger space, a retarding tongue at the front, and an end member for connecting said side members 110 whereby the tongue is spaced from the bottom, said bottom being cut away opposite the tongue for affording ample finger space for engaging the tickets when the guide is in use. 115

120 5. A ticket guide of the character described comprising a bottom member, a pair of side members, said side members being formed with projecting downwardly extending ends, a cross section connecting said ends 125 and presenting means for receiving a card, and a bendable tongue extending from the upper edge of said section positioned to prevent the removal of more than one ticket at a time. 125

130 6. A ticket guide of the character described comprising a bottom member, a pair of side members formed with forwardly and downwardly extending front ends, a transverse section connecting the front ends, and

a projection extending from said front end in the path of movement of the tickets from beneath, said bottom being cut away at the front so as to present ample space for the 5 passage of an operators finger back of said projection.

7. A ticket guide of the character described comprising a bottom member, a pair

of side members, each side member having a pair of projecting ears arranged therein adjacent one end, and a pair of forwardly and downwardly extending end members, a front section connecting the front ends of said end members, and an adjustable tongue extending from said section. 10
